UNITED STATES PATENT OFFICE.

JOSIAH T. WILCOX, OF WESTFIELD, NEW JERSEY, ASSIGNOR TO THE TIN DECORATING COMPANY OF BALTIMORE, OF BALTIMORE, MARYLAND, A CORPORATION OF NEW JERSEY.

SIFTER-TOP-RECEPACLE CLOSURE.

Application filed November 19, 1920. Serial No. 425,038.

To all whom it may concern:

Be it known that I, JOSIAH T. WILCOX, a citizen of the United States, and resident of Westfield, in the county of Union and State 5 of New Jersey, have invented certain new and useful Improvements in Sifter-Top-Receptacle Closures, of which the following is a specification.

My invention relates to a class of containers which is well exemplified by containers for talcum and similar toilet powders, consisting of sheet metal cans having a dispensing closure, preferably in the form of a sifter top, including a rotatable cap arranged to cover or uncover the powder discharge openings.

These cans, or boxes, are usually furnished in quantities, in a more or less completed condition, to manufacturers or packers of 20 toilet powder, who fill the cans, complete them by affixing a closure, and distribute them for sale.

In some cases the cans are furnished with the dispensing top in place, complete, and 25 with a filling opening in another part of the can, through which the powder is introduced, and this filling opening is then closed. The provision of a special filling opening involves additional expense in the production 30 of the cans and when the closure of this opening requires machine operations, added expense and other difficulties on the part of the packer are also involved. In other cases the can bodies are furnished with openings 35 which are to receive the dispensing closures and the closures are furnished separately, to be attached after the cans are filled through the closure openings. The attachment of the dispensing closures usually involves machine operations, which necessitate more or 40 less expensive equipment and occasions delays objectionable to manufacturers or packers of the toilet preparations. Also, regardless of the manner in which the cans are 45 filled, the dispensing closures as often constructed include a sleeve or part extending into the can body about the opening in which the dispensing top is inserted, and this inwardly extending portion traps some of the 50 contents of the box so that it is practically impossible for the purchaser to discharge the entire contents, and this, of course, reduces the value of the commodity to the consumer. In a certain class of containers for 55 these commodities, the can bodies have more

or less straight and parallel sides with a top opening of considerable area, sometimes polygonal or oval and often round in contour. These openings are closed by a top or breast which is comparable to the end cap of an ordinary tin can, and this top or breast may be crimped on or may be flanged and applied with a friction fit or otherwise permanently secured. Such a top affords an opportunity for easily forming in it before 60 it is placed on the can any suitable dispensing closure and in cans of this sort some of the difficulties mentioned above in connection with cans of other types are more readily avoided.

My invention aims to avoid the difficulties mentioned by providing a box or can suitable for toilet powders and the like having only one opening, which is necessarily provided to receive the dispensing closure, and 75 provided with a part of the closure structure inserted in the opening in the process of manufacture, this part having a relatively large open end through which the can can be easily and quickly filled; and providing an 80 additional closure part, separate from the can body structure, constructed and arranged to co-operate with the closure member attached to the can body, so that the separate part may be applied after the can 85 is filled without machine operations. The originally separate closure structure usually comprises a part to co-operate with the closure member located on the box body and another relatively movable part arranged to 90 control the dispensing openings. The closure structure is also constructed and arranged so that no part extends appreciably into the can body and, therefore, no appreciable amount of the contents of the container 95 is trapped within it, and full commodity value is thus afforded to the consumer.

The objects, characteristics and advantages of the invention are further explained 100 so far as necessary, in connection with a detailed description of the accompanying drawing, which shows one exemplifying embodiment of the invention. After considering this, persons skilled in the art will understand that many variations may be made in accordance with the principles disclosed and I contemplate the employment of any structures which are within the scope of the 105 claims.

In the drawings:

Fig. 1 is a vertical central section of the upper part of a container or can and dispensing closure embodying the invention;

5 Fig. 2 is a section in similar plane showing the can body and the closure member permanently attached to the body with other closure parts removed;

10 Fig. 3 is a separate detail in section of the friction member of the attachable closure structure;

Fig. 4 is a sectional view of the friction member with the rotatable cap attached;

15 Fig. 5 is a detail of the cap separated from the friction member;

Fig. 6 is a top plan of the complete closure in position on a container.

Figs. 1, 2 and 3 show a container C having a wall 10 provided with an opening 11, usually circular, through which the container may be filled and in which a closure member is located. In the process of manufacture the can body is provided with a closure member 15 which may be identified for convenience as a fixed closure member. This consists in the present case of an approximately cylindrical sleeve, which may be actually slightly tapered, so that the diameter is slightly larger at the inner end than at a point near the outer end. This thimble or sleeve is provided, by suitable pressing or bending operations, with a flange 16 consisting of parallel folds of the integral sheet metal of the sleeve and another flange 17 originally extending in cylindrical form below flange 16 and inserted in the filling opening and rolled or pressed outward as shown in Fig. 2, so that the two thimble flanges tightly grip the metal of the container wall 10 surrounding opening 11. The fixed closure member does not extend appreciably into the can body and no appreciable amount of the contents of the can can be trapped within it, and the discharge of the entire contents of the can for the use of the consumer is, therefore, assured. The outer end of sleeve 15 is usually curved slightly inward as at 18 to facilitate attachment of the separate closure structure.

50 The separate closure structure comprises a dished or cup-shaped member 20 having an approximately cylindrical wall 21 adapted to closely fit with frictional engagement, the outer surface of sleeve or thimble 15. The lower edge of this wall may be slightly flared out as at 22 to facilitate application of the separate closure structure to sleeve 15. The upper or outer wall 23 of member 20 is usually bulged slightly outward, or externally convex, and is provided with a suitable plurality of discharge openings 24. The outer wall 23 may also be provided with an outwardly pressed projection 25.

65 A rotatable cap 30 is produced by suit-

able pressing operations. This comprises an upper or outer wall 31 shaped to conform closely to the contour of wall 23 of member 20 and this wall 31 is provided with a suitable plurality of discharge openings 32 corresponding substantially in arrangement to the arrangement of openings 24. Otherwise the form of cap 30 may vary greatly, but usually it has a side wall 33 converging inward and downwardly and terminating in an inwardly curved edge 34 arranged to engage side wall 21 of member 20 with a rotatable fit. Outer wall 31 also has a short arch-shaped slot 35 adapted to receive projection 25 of member 20.

70 Cap 30 is placed over member 20 and secured by pressing portions of wall 21 outward, forming projections or ridges 40 lying above edge 34 of the cap so that the cap cannot be removed but may be rotated to the extent permitted by projection 25 lying in slot 35, to bring holes 32 and 24 into registry, or out of registry, to permit discharge of the container contents or to close the container as desired. A complete separate, attachable closure structure is thus produced as shown in Fig. 4.

75 The described structure and arrangement of the rotatable cap and member 20 provide in a simple way for the secure and rotatable attachment of the cap without the necessity for any rivet or other connection passing through the two members at their rotative center. The mode of attaching the rotatable cap by outwardly creasing the member 20 as 40, also provides in an advantageous way for the lateral enlargement of the cap at the sides of member 20, producing a rounded knob-like gripping surface at and about the points 45, Figs. 1 and 4. A space 46 is thus provided between the side wall of the rotatable cap and the adjacent wall of the member 20. This space affords opportunity for inwardly depressing the cap material at intervals, producing rounded knobs 47 and depressions 48 to further facilitate the gripping and turning of the cap and also to add to the decorative appearance of the closure.

80 Containers or cans are furnished to the manufacturer or packer of the toilet powder in the condition shown in Fig. 2, that is with only a single opening, provided with a fixed member or sleeve 15 through which the can can be easily and quickly filled. The separate closure structure is then attached without any machine operation and by ordinary unskilled labor, the method of attachment consisting simply in placing the cup-shaped member over the sleeve 15 and pressing it down, whereupon a firm frictional engagement is established between the walls 21 and 15, this engagement being substantially permanent and secure against any force that can ordinarily be applied to cap 30 in the proper use of the container. The 85

cap 30 may then be rotated to open or close the sifter openings in the ordinary way and the structure has, for all purposes of use after filling and application of the separate closure structure, the same simplicity and other characteristics as if attachable member 20 and sleeve 15 were originally integral.

By the described construction, therefore, the disadvantages incident to machine operations in completing the closure after filling the cans and incident to the necessity for providing a special filling opening, and other disadvantages previously pointed out, are avoided, and a dispensing closure of acceptable form and desirable simplicity is provided.

What I claim is:—

1. A dispensing closure of the class described, comprising a sleeve-like member secured in a filling opening of a can wall, a cup-like member tightly fitting the sleeve member and having an outer end provided with dispensing openings, and a rotatable cap enclosing the outer end of the cup-member and overlapping its sides and having an outer portion closely fitting the outer end of the cup-member and provided with co-operating discharge openings, the peripheral portion of the cap having substantial clearance from the side walls of the cup-member, the lower edge of the cap being inwardly

turned and engaging below a projection pressed in the cup-member so that the cap is secured against outward displacement and rotatably located without the provision of a pivot.

2. In a dispensing closure of the class described, a sleeve-like member having flanges secured in a filling opening of a can wall, a cup-like member having a friction fit on the sleeve member and having a convex outer end provided with dispensing openings, and a rotatable cap enclosing the outer end of the cup-member and overlapping its sides and having a convex outer portion closely fitting the outer end of the cup-member and provided with co-operating discharge openings, the peripheral portion of the cap being rounded and having substantial clearance from the side walls of the cup-member and having rounded alternate projections and depressions to facilitate gripping and turning, the lower edge of the cap being inwardly turned and engaging below projections pressed in the cup-member so that the cap is secured against outward displacement and rotatably located without the provision of a pivot.

Signed at city of Baltimore and State of Maryland this 16th day of November, A. D. 1920.

JOSIAH T. WILCOX.
